UNITED STATES PATENT OFFICE.

CHARLES F. SMITH, OF BRIDGEPORT, CONNECTICUT.

BAND-BRAKE.

1,036,360.

Specification of Letters Patent. Patented Aug. 20, 1912.

Application filed August 23, 1911. Serial No. 645,640.

To all whom it may concern:

Be it known that I, CHARLES F. SMITH, a citizen of the United States, and a resident of Bridgeport, in the county of Fairfield and State of Connecticut, have invented certain new and useful Improvements in Band-Brakes, of which the following is a specification.

This invention relates to band brakes and has for its object to provide a brake of the class specified of high efficiency, of simple construction and equally operable in either direction.

To these ends my improvements comprise parts and combinations of parts illustrated in their preferred form in the accompanying drawings wherein—

Figure 1 is a side elevation of my improved brake. Fig. 2 is a plan view and Fig. 3 is a sectional end elevation on line 3, 3 of Fig. 1 looking in the direction of arrow 1. Fig. 4 is an end elevation of a portion of Fig. 1 looking in the direction of arrow 4. Fig. 5 is a plan view of the band portion of my brake unwrapped and laid flat. Fig. 6 is a side elevation similar to Fig. 1 and illustrating a modification of my improvements. Fig. 7 is a view similar to Fig. 4 and illustrating a modification of the showing of said Fig. 4.

For convenience of illustration I have shown my improvements applied to an automobile type of vehicle, wherein supporting frame 2 of the machine has bearing 5 for the rotation therein of axle 6. Brake cylinder 7 is fixed to axle 6 for rotation therewith. Wrapped about said cylinder 7 is brake band 8 comprising a relatively short middle portion 9 and two portions 10, 11 extending circumferentially therefrom in opposite directions (Fig. 3). Said middle portion 9 is of full-width or approximately of the width of cylinder 7 while portions 10, 11 are of half-width and are widthwise oppositely disposed relatively to said middle portion 9, so that when said band 8 (Fig. 5) is wrapped around cylinder 7, ends 12, 13 of portions 10, 11 respectively, approximately meet said middle portion 9 and said band substantially encircles said cylinder and covers substantially all the face thereof. Said middle portion 9 is provided with ear 14 riveted thereto at 15, 15 and ends 12, 13 of portions 10, 11 have ears 16, 17 riveted thereto, all respectively. Said ear 14 is connected to ear 18 of frame 2 by bolt 19 and is slotted at 20 to permit move-
ment of said ear 14 and band 8 radially of axis 6 but not circumferentially thereof. Frame 2 is provided with ears 21, 22 in 60 which are pivotally mounted at 34, 35 one end of levers 23, 24 all respectively. The other ends of said levers are connected by links 25, 26 to opposite ends of rock lever 27, all respectively. Said rock lever 27 is fixed to shaft 28 mounted in bearing 29 in the outer end of ear 18. To the outer end of said shaft 28 is fixed arm 30 connected at its outer end with the usual pull rod 31. Ears 16, 17 are connected by links 32, 33 to 70 levers 23, 24 near pivots 34, 35 all respectively. Diametrically opposite middle portion 9 (Figs. 1 and 4) half-width portions 10, 11 are provided with means for circumferentially freeing band 8 from cylinder 7. 75 Said means comprise ears 36, 37 fixed to said portions 10, 11 respectively. Abutments 38, 39 inreaching from frame 2 have push screws as 40 mounted therein for engagement with springs as 41 interposed between 80 said ears 36, 37 and said push screws as 40. Thus by suitably adjusting said set screws band portions 10, 11 may be returned to their normal and inactive positions after 85 having been disturbed therefrom. If cylinder 7 is rotated in clockwise direction (Fig. 1) and rod 31 be pulled half-width portion 10 of band 8 will be wrapped around said cylinder with maximum effect and half-width portion 11 will have less effect as the 90 clockwise rotation of said cylinder tends to unwrap said portion 11. If cylinder 7 is rotated in anti-clockwise direction the relative efficiency of members 10, 11 will be reversed. It will thus be seen that my im- 95 proved brake is of equal efficiency when said cylinder is rotated in either direction. If it is desired to utilize the whole length of said band 8 for enwrapping cylinder 7 in the direction of its rotation the modification 100 of Figs. 6 and 7 may be employed. Therein ears 21, 22 of frame 2 are provided with stops or abutments 41, 42 for engagement with similar abutments 43, 44 of ears 16, 17 all respectively, of band 8. Middle ear 14 of band 8 is omitted and ear 18 of frame 2 is connected with shaft 28 by link 45 whereby said shaft and the parts supported thereon are sufficiently mobile to permit abutments 42, 44 to engage when cylinder 7 rotates in clockwise direction (Fig. 6). Then upon pulling rod 31 ear 16 is moved upwardly and the two coils of band 8 are wrapped around cylinder 7. If said cylin- 105 110

der 7 rotates in anti-clockwise direction abutments 41, 43 will engage and upon pulling rod 31, ear 17 will be moved downwardly and the two coils of band 8 will be wrapped around said cylinder in the opposite direction. With this modification I preferably employ the simple means of Fig. 7 for freeing the band circumferentially from said cylinder. Therein each member 10, 11 has an ear as 48 overhanging the other member and spring 47 is interposed between said ears to move said members 10, 11 circumferentially relatively to each other to cause abutments 43, 44 of ears 16, 17 to engage abutments 41, 42 of fixed ears 21, 22.

While my improvements are particularly adapted for vehicle brakes, as for instance for automobiles, they are obviously adapted for transmission means and it will be obvious to those skilled in the art that my improvements may be modified in many ways and applied to other ends than those illustrated all within the spirit and scope of my invention.

I am aware that flexible bands of uniform width substantially encircling a cylindrical drum and provided with toggle or cam means for drawing the ends thereof together to bind said cylinder are well known; also that helically wound frictional members of rope or metal of uniform width have been used for brake band purposes and I do not broadly claim such construction.

What I do claim is:

1. A band brake including in combination, a supporting frame, a cylinder mounted for rotation relative thereto, a flexible band about said cylinder comprising a relatively short middle portion of full-width and two widthwise oppositely disposed half-width portions extending circumferentially in opposite directions respectively from said middle portion, means for drawing the ends of said half-width portions to substantial meeting with said middle portion circumferentially toward each other and means, opposite the means for drawing the ends toward each other, for circumferentially freeing said band from said cylinder.

2. A band brake including in combination, a supporting frame, a cylinder mounted for rotation relative thereto, a flexible band about said cylinder comprising a relatively short middle portion of full-width and two widthwise oppositely disposed half-width portions extending circumferentially in opposite directions respectively from said middle portion to substantial meeting with said middle portion, means for drawing the ends of said half-width portions circumferentially toward each other and means opposite the means for drawing the ends toward each other for circumferentially freeing said band from said cylinder.

3. A band brake including in combination,

a supporting frame, a cylinder mounted for rotation relative thereto, a flexible band substantially twice encircling said cylinder comprising a relatively short middle portion of full-width and two widthwise oppositely disposed half-width portions extending circumferentially in opposite directions respectively from said middle portion to substantial meeting therewith, means connecting said band and frame for preventing said band from rotating with said cylinder, means for drawing the ends of said half-width portions circumferentially toward each other and means, opposite the means for drawing the ends toward each other, for urging the two half-width portions circumferentially in opposite directions for freeing said band from said cylinder.

4. A band brake including in combination, a supporting frame, a cylinder mounted for rotation relative thereto, a flexible band about said cylinder comprising a relatively short middle portion of full-width and two widthwise oppositely disposed half-width portions extending circumferentially in opposite directions respectively from said middle portion, means connecting said band and frame for preventing said band from rotating with said cylinder, means for drawing the ends of said half-width portions circumferentially toward each other and means, opposite the means for drawing the ends toward each other, for urging the two half-width portions circumferentially in opposite directions for freeing said band from said cylinder.

5. A flexible brake band adapted to be wrapped about a cylinder, comprising a relatively short middle portion of full-width, two widthwise oppositely disposed half-width portions extending lengthwise in opposite directions respectively from said middle portion to substantial meeting therewith and means, opposite the means for drawing the ends toward each other, for circumferentially freeing said band from said cylinder.

6. A cylinder, a flexible brake band adapted to be wrapped about said cylinder, comprising a relatively short middle portion of full-width and two widthwise oppositely disposed half-width portions extending lengthwise in opposite directions respectively from said middle portion to substantial meeting therewith, means for drawing said half-width portions toward one another about the cylinder and means, opposite the means for drawing the ends toward each other, for urging the two half-width portions circumferentially in opposite directions for freeing said band from said cylinder.

7. A cylinder, a flexible brake band adapted to be wrapped substantially twice around said cylinder, means for drawing the ends

of said band toward each other about said cylinder and means opposite said drawing means for urging the two portions of said band in directions opposite to the directions 5 respectively in which they are drawn by the end drawing means.

8. A cylinder, a flexible brake band adapted to be wrapped substantially twice about said cylinder, comprising a relatively 10 short middle portion of full-width and two widthwise oppositely disposed half-width portions extending lengthwise in opposite directions respectively from said middle portion to substantial meeting therewith, 15 means for drawing said half-width portions toward one another about said cylinder and means, opposite the means for drawing the half-width portions toward one another, for urging one portion of said band in a direction 20 opposite to the direction of rotation of the cylinder and means for urging the other portion of said band in a direction opposite to the direction of rotation of said cylinder when that cylinder is rotating in a direction 25 opposite to the first mentioned direction.

9. A band brake including in combination, a supporting frame, a cylinder mounted for rotation relative thereto, a flexible band about said cylinder, means for drawing the ends of said band circumferentially toward each other comprising opposite levers fulcrumed in said frame, a rock lever pivoted midway its length in said frame between said opposite levers, links connecting the free ends of said opposite levers with the ends of the rock lever, and links connecting said opposite levers with the ends 35 of said band.

10. A band brake including in combination, a supporting frame, a cylinder mounted for rotation relative thereto, a flexible band about said cylinder, means for drawing the ends of said band circumferentially toward each other comprising opposite levers fulcrumed in said frame, a rock lever pivoted midway its length in said frame between said opposite levers, links connecting the free ends of said opposite levers with the ends of the rock lever, links connecting said 45 opposite levers with the ends of said band, and means for adjusting the lengths, respectively, of one pair of links.

11. A band brake including in combination, a supporting frame, a cylinder mounted for rotation relative thereto, a flexible band about said cylinder comprising a relatively 55 short middle portion of full-width and two widthwise oppositely disposed half-width portions extending circumferentially in opposite directions, respectively, from said middle portion to an approximate meeting

with said middle portion, means for drawing the ends of said half-width portions circumferentially toward each other comprising opposite levers fulcrumed in said frame, 65 a rock lever pivoted midway its length in said frame between said opposite levers, links connecting the free ends of said opposite levers with the ends of said rock lever, and links connecting said opposite levers 70 with the ends of said half-width portions.

12. A band brake including in combination, a supporting frame, a cylinder mounted for rotation relative thereto, a flexible band about said cylinder comprising a relatively 75 short middle portion of full width and two widthwise oppositely disposed half-width portions extending circumferentially in opposite directions, respectively, from said middle portion to an approximate meeting 80 with said middle portion, means for drawing the ends of said half-width portions circumferentially toward each other comprising opposite levers fulcrumed in said frame, a rock lever pivoted midway its length in 85 said frame between said opposite levers, links connecting the free ends of said opposite levers with the ends of said rock lever, and links connecting said opposite levers with the ends of said half-width portions, and 90 means for holding the middle portion of said band against rotation relative to said frame.

13. A band brake including in combination, a supporting frame, a cylinder mounted for rotation relative thereto, a flexible band about said cylinder comprising a relatively 95 short middle portion of full-width and two widthwise oppositely disposed half-width portions extending circumferentially in opposite directions, respectively, from said middle portion to an approximate meeting with said middle portion, means for drawing the ends of said half-width portions circumferentially toward each other comprising opposite levers fulcrumed in said frame, 100 a rock lever pivoted midway its length in said frame between said opposite levers, links connecting the free ends of said opposite levers with the ends of said rock lever, links connecting said opposite levers with the ends of said half-width portions and 105 means for adjusting the lengths, respectively, of one pair of links.
